UNITED STATES PATENT OFFICE.

ERNST LUDWIG ANDREAS HEIMLICH, OF BREMEN, GERMANY.

APPARATUS FOR OBTAINING THE BAST OF STALKED PLANTS.

Application filed February 3, 1927, Serial No. 165,744, and in Germany February 6, 1926.

The invention relates to an apparatus for obtaining the bast of stalked plants.

The principal object of the present invention is to provide a feeding means for the stalks which will automatically accommodate itself to various sizes of stalks and which will deliver the stalks to a cutter which divides the stalks longitudinally in halves, the halves being thereafter deflected and the woody envelope surrounding the fibers cut away.

An example of the form of an apparatus for carrying out this operation is represented in the drawings.

15 Fig. 1 shows a front view of the improved apparatus.

Fig. 2 a side view of the same.

Fig. 3 a rear view of the same.

Fig. 4 a plan view of the same.

20 Fig. 5 shows a longitudinal section on line 5—5 of Fig. 2.

Fig. 6 is a cross-section on line 6—6 of Fig. 5.

Fig. 7 shows, in front view and on an enlarged scale, one of the toothed discs used for stripping the woody envelope from the halved stalks.

25 Fig. 8 illustrates a modified means for the automatic adjustment of the endless bands forming the stalk feeder.

The improved apparatus comprises a stalk feeding means for the delivery of the stalk to the halving cutter. This feeding means comprises two endless bands 3 and 3^a respectively mounted on band wheels 1 and 1^a and 2 and 2^a, the arrangement being such as to cause the bands to define a pathway through which the stalks, indicated at 5, are fed longitudinally through the gripping action of the bands 3 and 3^a thereon. These bands 3 and 3^a define the side walls of a stalk path or passage, the upper and lower walls of which are formed by plates 12^a and 12, as indicated in Fig. 6 of the drawings.

30 At the outlet end of the feeding passage formed by the bands 3 and 3^a is arranged a cutting tool 4 which, by reason of its triangular formation, serves to divide the stalk longitudinally and into approximate halves. On the respective sides of the cutter are rails 6 and 6^a, the proximate surfaces of these rails and the sides of the cutter forming a restricted passage for each half of the stalk, as clearly indicated in Fig. 5.

35 The inlet ends of the passageways for the half stalks is flared by correspondingly form-

ing the surface of each rail and the stalks at the outlet ends of these restricted passageways are intercepted by cutting discs 7 and 7^a, shown more particularly in Fig. 7 of the drawings, which discs are provided with cutting projections to cut away the woody envelope of the halved stalk. The bast fiber remaining after the woody envelope is cut away by the cutting discs is directed laterally onto endless bands, indicated at 8 and 8^a, adapted for travel over rolls 9 and 10 and 9^a and 10^a respectively, rollers 11 and 11^a cooperating with the bands 8 and 8^a to insure a feeding pressure on the bast. 70

As the stalks to be handled by the apparatus will necessarily be of varying diameters, it is of course necessary that the endless bands 3 and 3^a be capable of relative adjustment in order to accommodate the different diameters 75 of stalks with which the machine may be used. Such automatic compensating means, as illustrated in Fig. 5, comprises angle arms 14 and 14^a pivotally supported on pivots 15 and 15^a and carrying at 15^b and 15^c the 80 bars on which the pivots 13 and 13^a of the band rollers 1 and 2 are mounted. The downwardly extending portions of the angle arms are connected by a spring or springs 16. Obviously, the bands will automatically accommodate themselves to stalks of varying diameters to a degree sufficient to insure proper feeding of the stalks. 85

A modification in this respect is illustrated in Fig. 8 wherein the arms 13 and 13^a which carry the pivots of the band rollers 1 and 2 are connected at 15^b and 15^c, which are stationary pivots, to arms 15^d and 15^e terminating in rolls 17 and 17^a and exerting tension on those portions of the bands 3 and 3^a beyond the stalk feeding path. Here, the bands automatically accommodate themselves to different diameters of stalks and at the same time there is maintained a proper tension on the bands to permit them to be operated by the rolls. 100

It is of course important that the respective bands forming the feeding means be maintained equally on opposite sides of the cutter 4 in all adjustments. To secure this 105 result, the shafts of the band rollers 1^a and 2^a are supported in arms 19 and 19^a moving about fixed pivots 18 and 18^a.

Rods 20 and 20^a are connected to the respective arms 19 and 19^a beyond the roller shafts relative to the pivots of the rods and these rods 20 and 20^a are in turn connected 110

to an angle lever 21 pivoted at 23, the rod 20 having an adjustable connection with the lever 21 through the medium of a slot 21^b. The arm 21 of the angle lever is adjustable 5 in the slide 21^a and is terminally connected to a bar 22 slidably mounted in a cylinder 24 and under the pressure of a spring (not shown) in said cylinder. The spring exerts its tension in the direction of the arrow 10 (Fig. 1) and the connection obviously insures that any movement of the band roller 1^a or 2^a will be correspondingly and similarly communicated to the other roller to insure that the bands 3 and 3^a at their outlet or 15 delivery end shall be equally spaced relative to the entering point of the cutter 4.

The machine is operated by a motor 25 acting through belts 28 and 29 passing over belt wheels 26 and 27 secured to the shaft 20 to the motor to drive the various parts of the apparatus. The belt 28 operates over belt wheels 30, 31 and 32, while the belt 29 tensioned by the roller 33 under the influence of the weight 33^a operates to drive a belt wheel 25 34 on the shaft of which is arranged a belt wheel 35 connected by a belt 37 with belt pulleys 38 and 39 mounted on the shafts of belt rollers 1^a and 2^a, the belt 37 passing also over a belt wheel 40. The belt wheel 30 30 and also the belt wheel 40 are belt tensioning means operating by means of weights 30^a and 40^a, all as clearly shown in Fig. 3. The belt wheels 31 and 32 are fixed on the shafts of the cutting discs 7 and 7^a.

35 What I claim to be new is:

1. In an apparatus for treating stalks to remove the fiber, a stalk feeding means comprising endless belts travelling in parallel relation to grip and feed the stalk, a cutter 40 arranged at the end of the feeding means to divide the stalk in half, means for deflecting the halves of the stalks in opposite directions, and cutting discs for removing the woody envelopes of the stalks immediately 45 at the point of their deflection.

2. In an apparatus for treating stalks to remove the fiber, a stalk feeding means comprising endless belts travelling in parallel relation to grip and feed the stalk, means 50 for automatically adjusting the feeding means to compensate for stalks of varying diameters, a cutter arranged at the end

of the feeding means to divide the stalk in half, means for deflecting the halves of the stalks in opposite directions, and cutting 55 discs for removing the woody envelopes of the stalks immediately at the point of their deflection.

3. In an apparatus for treating stalks to remove the fiber therefrom, consisting in a 60 feeding means made up of independent endless belts adapted for travel in parallel relation throughout a determinate length to provide for gripping and feeding the stalks longitudinally, a triangular cutter arranged 65 at the delivery end of the feeding means for dividing the stalk in halves, means for automatically compensating for stalks of different diameters in the feeding means, means for automatically maintaining the feeding means 70 in proper relation to the cutter in all compensating movements of said feeding means, rails arranged on each side of the cutter and cooperating therewith to provide diverging guideways for the respective halves of the stalk, and discs arranged immediately at the 75 termination of said guideways to cut away the woody envelope of the halved stalks.

4. In an apparatus for treating stalks to remove the fiber therefrom, consisting in a 80 feeding means made up of independent endless belts adapted for travel in parallel relation throughout a determinate length to provide for gripping and feeding the stalks longitudinally, a triangular cutter arranged 85 at the delivery end of the feeding means for dividing the stalk in halves, means for automatically compensating for stalks of different diameters in the feeding means, means for automatically maintaining the feeding 90 means in proper relation to the cutter in all compensating movements of said feeding means, rails arranged on each side of the cutter and cooperating therewith to provide diverging guideways for the respective halves 95 of the stalk, discs arranged immediately at the termination of said guideways to cut away the woody envelope of the halved stalks, and means arranged beyond the discs to feed the fiber away from the discs. 100

In testimony whereof I have affixed my signature.

ERNST LUDWIG ANDREAS HEIMLICH.
